UNITED STATES PATENT OFFICE.

LUDWIG OBERHAMMER, OF MUNICH, GERMANY.

AUTOMATIC OR SELF-LOADING SMALL ARM.

Application filed May 27, 1926, Serial No. 112,049, and in Germany June 17, 1924.

My invention relates to automatic breech-loading fire-arms and more particularly to small-arms of the magazine-pistol type in which the several operations of unlocking 5 and opening the breech after firing a shot, ejecting the empty cartridge shell, cocking the percussion member, introducing a fresh cartridge into the cartridge chamber of the barrel and so on are automatically brought 10 about by the recoil of the breech-bolt for closing the breech or rear end of the said cartridge chamber, and by means of a semi-tubular extension to inclose the top and sides of the barrel and which is integral with the 15 breech-bolt to form a movable or reciprocating unit therewith.

The chief object of my invention is to provide a small-arm of the stated type which will afford perfect safety inasmuch as a premature or accidental shot cannot occur since the lock mechanism is so constructed as to prevent the percussion member from being retained in cocked position when the breech is manually opened in case of loading or unloading the pistol, whereas upon the discharge of a cartridge the hammer will be cocked, that is to say, retained in full-cock position, automatically, as usual in arms of the kind, and the pistol will be ready for 30 the next shot. In case of firing the first shot the hammer is operated by the trigger through the agency of the trigger bar just in the manner of an ordinary pistol of the revolver type.

Fire-arms of the stated class as hitherto constructed are objectionable or unsatisfactory inasmuch as by withdrawing the breech-block by hand for the purpose of introducing the first or uppermost cartridge into the cartridge chamber of the barrel, the hammer will be cocked for firing at the same time. This condition of the pistol is a source of danger and many attempts have been made heretofore to remedy the defect, but as far 45 as my knowledge goes the problem has not been solved as yet in a practical and satisfactory manner.

According to my invention the percussion member, either a hammer or a percussion bolt, is automatically prevented by the lock mechanism from being moved to full-cock, when the breech-block has been withdrawn by hand; and in case the hammer or the percussion bolt, in consequence of a previous

shot, is in its full-cock position, the manual 55 withdrawal of the breech-block will cause the same to be uncocked. Thus the pistol, although not distinguished in its outer appearance from a self-loading small-arm of the usual type as hitherto constructed, yet 60 affords, owing to its improved mechanism, the important advantage of being uncocked upon the withdrawal of the breech-block either for loading purposes or just for the purpose of uncocking the cocked pistol. 65

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims 75 are expressed.

In the accompanying drawings forming a part of this specification and showing diagrammatically, for purposes of exemplification, a few preferred forms in which the invention may be embodied and practised:—

Figure 1 is an elevation or side view of the pistol with the breech-block and the rear portion of the semi-tubular extension thereof broken off and with the magazine and the side wall of the handle removed, the parts of the mechanism being shown in the position which they assume upon the operation of the trigger, while the pistol is not loaded; Figure 2 is a similar view showing the parts 90 in position after the opening and closing of the breech by hand, say for loading the pistol; Figure 3 is a similar view showing the parts with the hammer in the fully-cocked position; Figures 4 and 5 are detail views of 95 parts to be referred to; Figure 6 is a right-hand side elevation of the pistol similar to Figure 1, showing the construction in a percussion-bolt operated pistol; Figure 7 is a similar view showing the percussion-bolt 100 and co-operating parts in the cocked position; Figure 8 shows the hammer and the sear for holding it in cocked position; Figure 9 is a longitudinal section of the rear portion of the pistol with the handle and barrel broken away; Figures 10 and 11 are detail views illustrating the percussion bolt 105 in cocked position and in the position when

the breech-block is withdrawn, respectively; Figure 12 is a side view of the pistol with the handle in section and partly broken off and with parts removed to show the hammer 5 and the sear with a co-operating releasing lever; Figure 13 is a similar view showing the parts in a different position; Figure 14 is a side view of a further modification with parts removed for clearness sake and Figure 10 15 is a similar view with the operating parts shown in a different position.

Referring to Figures 1 to 5, 1 denotes the handle or grip, 2 is the breech-block or, more properly speaking, the semitubular extension of the block with the latter broken off; 3 denotes the trigger-guard, 4 is the trigger and 5 is the hammer. The trigger bar 6 is shaped to form a three-armed member for the particular purposes hereinafter referred to. As will be seen in Figures 1, 2 and 3, the bar 6 has an upper shank or arm 7, a lower arm 8 and a third arm 9 intermediate the two arms 7 and 8, all the three arms extending rearwards in front of the chamber for the reception of the cartridge magazine or holder (not shown). The hammer 5 has a lateral projection or nose 10 adapted to engage a suitable shoulder or recess 11 of the upper arm 7. The catch-lever or sear 12 for holding the hammer in its cocked position (i. e., at full-cock) and for releasing the same upon operation of the trigger, is pivotally mounted on a transverse pin 13. The sear 12 has a lateral projection or nose 14 and its lower end is bent to form a locking hook 15, see Figure 5, adapted to engage in a recess 16 of the trigger bar located just in front of the lower arm 8, which latter is stepped and adapted to co-operate 35 with the above mentioned nose 14 of the sear 12. The trigger bar is pivotally connected at its forward end to the trigger and normally tends to move slightly upward under the influence of a small spring (not shown) which is seated in a slot in the trigger and is coiled around the trigger bar pivot, this spring also tending to move the trigger forward. The upward movement of the bar causes nose 10 to engage recess 11. 40

The third or intermediate arm 9 of the bar 6 is bent and shaped to form a hook which is adapted to engage the pin sear 13 and thus support the bar. The hammer 5 and the arresting or catch lever or sear 12 are shown separately in Figures 4 and 5, respectively. The hammer has a recess 17 at its lower end for the top end 18 of sear 12 to engage in for holding the hammer in cocked position. 19 is the pivot pin of the hammer. 55

60

As regards the operation, Figure 1 shows the position of the parts upon the actuation of the trigger when or while the pistol is not loaded. The hammer occupies its foremost position in contact with the firing pin

(not shown), and its nose 10 is above the shoulder or recess 11 of the trigger bar arm 7. On pulling the trigger, the hammer will remain at rest because there will be no engagement of the parts 10 and 11 when the bar moves rearwards. In case of opening and closing the breech by hand, however, as is required for loading the pistol, the hammer will be pushed backwards away from the firing pin and will ultimately assume its operable or half-cock position represented in Figure 2, in which the nose 10 is engaged with recess 11, due to the action of the trigger spring, as previously described, while the end of arm 9 rests on sear pin 13 and the lower edge of arm 8 engages the upper end of hook 15, so that the pistol is then ready for firing the first shot. In this position, the engagement of the parts 10 and 11 holds the hammer at half-cock and prevents it from contacting with the firing pin, while the engagement of parts 9 and 13 prevents arm 7 from slipping down and releasing the hammer, since the arms 7 and 9 are integral parts of the trigger bar. If now the trigger be pulled, the trigger bar will be moved rearwards bodily; and its shoulder or recess 11, acting on the hammer nose 10, will turn the latter rearwards until disengagement of the parts 10 and 11 occurs, whereupon the hammer 95 will fly forwards to fire the first shot.

In opening the breech by hand, the breech block or slide 2 is moved completely backwards, pushing the hammer with it into the "over-pull" position represented in full lines in Figure 8; that is to say, a position beyond that of full-cock (indicated in dotted lines). In this position, the sear 12 is correspondingly lowered (i. e., turned or rocked slightly in a downward or clockwise direction) by 105 the cam-shaped heel of the hammer beyond notch 17, which heel or cam bears against the pointed sear nose 18 and moves it away from said notch, at the same time moving the sear hook 15 away from the trigger bar 110 arm 8. As the turning movement of the sear brings it entirely out of contact with the trigger bar, the latter and the trigger can then move slightly forward under the influence of the previously-mentioned trigger 115 spring; whereby the recess 16 in the bar arm 8 is brought out of line with hook 15. The several movements take place, as will be understood, during the rearward motion of the breech block; and during its return motion, 120 the hammer moves forward until it is arrested at half-cock by the engagement of its nose 10 with the recess or shoulder 11 of the trigger bar. 125

When the first shot is fired (and thereafter at each succeeding shot), the recoil drives the breech block backwards, the parts moving in the same way as before. But in this case, however, the trigger is held in its rear position due to the pressure which is 130

maintained (more or less unintentionally) upon it, and the trigger bar 6 is likeways held back, so that its recess 16 remains over the hook 15. Hence, when the block executes its forward or return stroke, and the hammer likewise moves forward from its over-pull position, the sear will be free to swing in a counter-clockwise direction about its pivot 13, under the influence of the spring 0 associated with it (Figures 1-3), its nose 18 entering the hammer notch 17 and holding it at full-cock while its hook 15 engages in recess 16 and prevents any further forward movement of the trigger and its bar. If 5 now the breech block be opened and closed by hand to unload the pistol, its rearward movement will cause the hammer to cam the sear nose 18 out of engagement with its notch 17 and to withdraw the hook 15 from recess 10 16. Then, during the succeeding closing or forward movement of the breech block, the hammer will move forward into its half-cocked position. Consequently, it will be seen that the hammer will always be brought 15 into the position mentioned by a manual opening and closing of the breech, whether the cartridge chamber be loaded or empty at such time. In the former instance, moreover, and assuming that the hammer is at 20 full-cock, the operation in question will change the hammer from full-cock to half-cock or, stated otherwise, will uncock it.

The breech-block will act, upon its rearward movement after firing a shot, to turn 25 the hammer about its pivot sufficiently to allow the breech to pass over it and at the subsequent forward movement of the breech under the action of the usual restoring spring the hammer will remain in full-cock position owing to the engagement of the pawl-like sear end 18 in the recess 17 of the hammer.

In order to ensure the cocking engagement of the parts 17 and 18, the hammer 30 must be forced rearwards a little beyond the full-cock position. In case, however, the breech is opened by hand, the hammer will be moved likewise a little beyond its full-cock position even if the hammer is cocked 35 or occupies the full-cock position, so that the pawl-like sear end 18 will not engage in the recess 17 or, as the case may be, will disengage therefrom, but in this eventuality the hooked end 15 of the sear 12 will catch into 40 the recess or notch 16 of the sear, as soon as the latter commences its return movement, so that the co-operating parts 18 and 17 cannot engage and the hammer must return into its half-cock or rest position shown 45 in Figure 2, simultaneously with the manual operation of closing the breech.

Figure 3 illustrates, as above stated, the 50 position of the parts when cocked upon the firing of a shot. The hammer is locked in its turned-down or full-cock-position by

the end 18 of the sear 12 engaging in the recess 17 of the hammer, and the hooked end 15 of the sear 12 engages in the recess 16 of the trigger bar so that the sear is locked and cannot turn about its pivot pin 13. The locking of the sear 12 prevents at the same time the co-operating parts 18 and 17 from disengaging, so that the discharge of a cartridge by inadvertence or accidentally cannot occur and a shot cannot be fired except when the trigger is operated for the purpose. When that takes place, the rearward movement of the trigger bar causes its arm 8 to exert pressure on the lateral projection or nose 14 of the sear 12 and the latter will be turned about its pivot pin 13 so as to disengage its pawl-like end 18 from the notch 17 of the hammer, whereupon the released hammer will fly forwards and a shot will be fired.

The modification illustrated in Figures 6 and 7 shows a pistol having a percussion bolt in lieu of a hammer, the bolt being designated 20 and shown as provided with a cocking nose or projection 21. The trigger bar 6 and trigger 4, in this instance, are made in a single piece, or otherwise rigidly connected together, and the former projects at its front end into the path of the breech block, so that when the block is moved rearwards to open the breech it will engage and move the trigger bar with it in the same direction. The said bar is provided with a stud 22 against which the free upper end of the front arm of a spring 23 exerts a constant pressure, and the handle 1 of the pistol is formed with a projection 24 that stud 22 normally rests against, thereby providing a support for the cocking nose 25 of the trigger bar, all as represented in Figure 6.

The figure just mentioned shows the parts in normal position, with the bolt 20 at half-cock and its nose 21 behind and engaged with the cocking nose 25 on the trigger bar; the bolt being subjected to the action of the firing spring 26, which in this position is expanded, but being prevented from contacting with the primer of the cartridge by the engagement of the parts 25, 21. Beyond the nose 25 a recess 16 is formed in the lower edge of the trigger bar, and beyond this recess in turn there is a beveled head 28 on the bar for coaction with the hook 15 on the sear 12. The latter is also provided, as before, with a pointed portion 18 for engagement with a lug or notch 17 formed at the bottom of the bolt 20 at the rear end thereof, such engagement locking the bolt in its cocked position (Figure 7). A pin 27 extends horizontally across the rear portion of the sear, and a spring 28 is located beneath the sear and pushes it upwards, thus keeping it in contact with said pin. Finally, an auxiliary bar 30 is utilized to release the cocked bolt, this bar being actuated directly by the trigger 4 and terminating at its rear

end in a beveled head which depresses the sear and thus disengages it from the bolt.

The operation of this form is substantially the same as that of the first form. Starting with the initial opening and closing of the breech to load the pistol, and with the parts in Figure 6 position, the breech block is first moved rearwards by hand, carrying with it the trigger bar 6 and the bolt 20, until the head 28 of the bar extends over the sear hook 15, thus depressing the sear and preventing the pointed end 18 from catching the lug or notch 17 of the bolt. The breech block is then moved forwards to close the breech, during which time the parts 20 and 6 are free to move in the same direction under the pressure of their respective springs 26 and 23 until the trigger bar is arrested by the engagement of its stud 22 with projection 24, all parts then being restored to Figure 6 position.

On firing the first shot, the trigger bar is pulled all the way back, until its beveled head 28 finally encounters the pin 27 and is depressed thereby in order to disengage its nose 25 from the nose 21 of the bolt, which latter thereupon flies forwards under the action of its spring 26 to fire the shot. The sear itself is depressed as the head 28 passes over it, but immediately afterwards is raised by its spring 29, its shoulder or hook 15 moving into the recess 16 which is then directly above it. This upward movement of the sear engages the parts 18 and 17 during the succeeding recoil movement of the bolt with the breech block so that the bolt is thus locked in full-cock position (Figure 7); the trigger being held back, of course, by the pressure of the trigger finger against it. The next shot is fired through the intermediary of the auxiliary bar 30 which acts as a connector between the trigger and the sear, just as is the case with the Browning pistol, being pressed rearwards by the trigger and, in turn, depressing the sear to disengage the parts 18 and 17.

Uncocking can be effected, as before, by moving the breech block backwards by hand far enough to enable a releasing nose 39 on the under side of the bolt to engage the nose 18 of the sear and thereby rock the latter downwards so as to withdraw hook 15 from recess 16 in the trigger bar, at the same time disengaging the parts 18 and 17, so that the moving parts are then free to return to the normal or half-cock position illustrated in Fig. 6.

It will be seen that the operation of the fire-arm shown in Figures 6 and 7 is similar to that of the embodiment shown in Figures 1 to 5, in particular the same idea or problem is realized in both embodiments; that is to say, in case of opening the breech by hand the spring-controlled trigger will move forwards and prevent the hammer from being

cocked for firing; or should the hammer at the time occupy the full-cock position, it will cause the same to return to its half-cock or rest position, whereas upon the firing of a shot the lock mechanism will automatically be brought to full-cock position so that firing may be continued without any interruption, as usual in fire-arms of this type, until the magazine is empty.

It will be evident that a high degree of safety is ensured according to the present invention. But the importance of the latter does not only reside in the fact of having a loaded, uncocked and safe fire-arm at disposal, but lies also in the fact that the first discharge requires a somewhat longer time for cocking and firing owing to the long path the trigger has to be moved for the purpose so that the shot, if fired at all, will be fired deliberately, whereas the firing speed of the subsequent discharges is not reduced since the then full-cocked lock mechanism requires a short withdrawal of the trigger only.

Figure 9 illustrates a further modification in which the releasing nose 39 forms part of or is integral with the bolt portion of the breech block 2. The pistol is shown fully opened so that the nose 39 has lowered or depressed the sear or catch lever 12 so as to prevent the nose 18¹ of the latter, with the aid of the arm 15, from engaging with the co-operating nose or recess 17¹ of the bolt 20.

Figures 10 and 11 show separately the percussion bolt 20 with the sear 12 in engaged position (that is, with the bolt cocked) and out of engagement (that is, when the breech is fully opened) respectively. In this modification the nose 39 is integral with the percussion bolt.

Figures 12 and 13 illustrate a modification in which a hammer 5 is employed for actuating the percussion bolt or pin and the releasing nose 39 forms part of the breech block 2. In this modification a releasing lever 40 is provided to co-operate with a pin 41 on the sear 12 in order to lower or depress the latter into the idle position in which the pawl-like end 18 cannot engage in the notch 17 of the hammer for cocking purposes, as will be seen in Figure 13, whereas Figure 12 shows the parts in cocked position.

Figures 14 and 15 illustrate a modification in which the sear 12 is operated by a spring-controlled pin or plunger 42, adapted to oscillate about a transverse axis 43. When the trigger 4 with the trigger bar 6 is in its foremost position, as in Figure 14, the spring-controlled pin or plunger 42 is held to occupy a vertical position, but when the trigger is in its rearmost position, as shown in Figure 15, the pin or plunger 42 occupies an inclined position. It will be seen that in the latter case the trigger bar 6 engages the plunger 42 causing it to turn or oscillate about its pivot pin 43, whereby the co-oper-

ating parts 17 and 18, see Figures 4 and 5, or the co-operating parts 25 and 21, see Figures 6 and 7, are caused to engage so that the pistol will be cocked. In the other case, 5 see Figure 14, the co-operating parts aforesaid, however, cannot engage.

In this modification the trigger 4 is integral with the trigger bar 6 and the spring-controlled pin or plunger 42 is encased in a 10 housing or sleeve 44 having a lateral projection 45 at its upper end. The depending arm 46 of the bar 6 is fitted with a pin 47 adapted to engage the said projection 45 when the trigger is withdrawn from the 15 position shown in Figure 14 to the position illustrated in Figure 15, and to tilt the sleeve 44 with the plunger housed therein, over to the position shown in Figure 15, whereby the plunger 42 is caused to turn or lift the 20 sear 12 from the position illustrated in Figure 14 to the position shown in Figure 15 with the co-operating parts 17 and 18, Figures 4 and 5, or the like in engagement, so that the pistol will be cocked. To this end 25 the sear 12 has an inclined face 48 just below its pivotal axis or pin 49 and the parts are arranged in such a manner that the point of contact between the plunger 42 and the said surface 48 is in front of the vertical plane 30 of the pivot 49 of the sear in the one case, Figure 14, while the contacting point thereof is in rear of the said plane in the other case, Figure 15.

I have not attempted to explain all of the 35 members and minute details of the construction of the automatic breech-loading pistol, for it will be understood by those to whom this specification is addressed, that the parts will necessarily be of the proper size and 40 relationship, and will be properly mounted and supported according to the tenets of the construction of recoil-loading small-arms of the type to which my improved pistol belongs; nor have I attempted to illustrate the 45 parts in their exact sizes and dimensions as many of the parts are conventionally shown.

It also appears unnecessary to reiterate the operation of the pistol, for the operation 50 of the essential parts has been described in detail; nor does it seem necessary to burden this specification with an exposition of the advantages which the invention possesses, for they will be apparent to those skilled in 55 the art to which this invention relates.

What I claim is:—

1. In a recoil-operated pistol, a percussion element; a catch for holding it in fully-cocked position; an arm on the catch; a 60 sliding breech block; and a trigger bar provided with means for cooperation with said arm, when the breech block is moved rearward by hand to open the breech, to prevent the catch from arresting the percussion element in fully-cocked position or, if said

catch occupies its arresting position, to move it out of such position and thereby release said element.

2. In a recoil-operated pistol, a percussion element having a notch therein; a catch 70 having a pointed end engageable in said notch to hold the percussion element at full-cock and also having a locking arm; and a trigger bar cooperative with said catch in cocking and uncocking said element and 75 having a recess for engagement by said arm.

3. In a recoil-operated pistol, a percussion element having a notch therein; a catch having a pointed end engageable in said notch to hold the percussion element at full-cock 80 and also having a locking arm; a trigger bar cooperative with said catch in cocking and uncocking said element and having a pair of recesses, one of which is adapted to receive said arm and thereby enable the 85 engagement of said catch end in said notch; and a projection on said percussion element engageable in the other recess in the trigger bar to effect firing of the first shot.

4. In a recoil-operated pistol, the combination of a trigger; a hammer provided with a nose; a pivotally-mounted catch having a projection; and a trigger bar pivoted at one end and provided with three arms, one for cooperation with said nose, another 95 for cooperation with the pivot of the catch, and the third for cooperation with the projection on said catch.

5. In a recoil-operated pistol, a striker; a sear for holding it at full-cock; a trigger; 100 a trigger bar connected to move therewith and engaged by the sear when the striker is cocked; and a sliding breech block operable, when moved by hand to open the breech, to disengage the sear from the trigger bar and 105 uncock the striker.

6. In a recoil-operated pistol, a striker; a sear for holding it at full-cock; a trigger; a trigger bar connected to move therewith and having a recess engaged by the sear 110 when the striker is cocked; and a sliding breech block operable, when moved by hand to open the breech, to disengage the sear from the trigger bar recess and uncock the 115 striker.

7. In a recoil-operated pistol, a striker; a sear for holding it at full-cock; a trigger; a trigger bar connected to move therewith and engageable by the sear when the trigger is retracted and the striker is cocked; a 120 sliding breech block operable, when moved by hand to open the breech, to disengage the sear from the trigger bar and uncock the striker; and means for automatically moving the trigger bar and trigger forwards 125 when such disengagement takes place to prevent reengagement.

8. In a recoil-operated pistol, a striker; a sear for holding it at full-cock; a trigger; a trigger bar connected to move therewith 130

and having a recess engaged by the sear when the trigger is retracted and the striker is cocked; a sliding breech block operable, when moved by hand to open the breech, to disengage the sear from the trigger bar recess and uncock the striker; and means for automatically moving the trigger bar and

trigger forwards when such disengagement takes place to bring the former into position to prevent reengagement of its recess by the sear. 10

In testimony whereof I affixed my signature.

LUDWIG OBERHAMMER.
